UNITED STATES PATENT OFFICE.

FRANK A. MCGUIRE, OF IOLA, KANSAS.

NON-RESEALABLE BOTTLE.

1,072,139.

Specification of Letters Patent. Patented Sept. 2, 1913.

Application filed February 17, 1913. Serial No. 749,001.

To all whom it may concern:

Be it known that I, FRANK A. MCGUIRE, a citizen of the United States, residing at Iola, in the county of Allen and State of Kansas, have invented certain new and useful Improvements in Non-Resealable Bottles; and I do hereby declare the following to be a full, clear, and exact description of the invention, such as will enable others skilled in the art to which it appertains to make and use the same.

This invention comprehends improvements in bottles and relates more particularly to those of the type which cannot be resealed after the seal has once been broken.

The primary object of the invention resides in the provision of a bottle of this nature which shall be of extremely simple construction, cheap to manufacture, and which may be closed in the usual manner.

Another and more specific object of the invention resides in the provision of a bottle having a stem projecting inwardly from the bottom thereof and formed with a fragile loop at its extremity, a hooked rod carried upon the stopper for engagement with said loop, whereby when the stopper is removed the loop will be broken, and a cup surrounding the stem to retain the particles of glass within the bottle.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawings, 40 in which—

Figure 1 is a longitudinal sectional view through a bottle constructed in accordance with my invention, parts thereof being shown in elevation, and, Fig. 2 is a detail view showing the connection between the hooked rod and fragile loop. Fig. 3 is a top plan view of the stem formed within the bottle.

Referring in detail to the drawings by numerals, 5 designates a bottle, which may be of any desired shape, and 6 indicates an inwardly projecting stem formed centrally of the bottom 7 of the bottle. The stem is of glass and has a fragile loop 8 formed on its inner extremity.

The stopper 9 has secured to its inner end

by any suitable means, such as the cap 10, an inwardly projecting rod 11. The rod is of spring-metal and has a hook 12 formed upon its free end which is adapted to snap into engagement with the loop 8 when the stopper is inserted into the bottle.

The inner end of the stem which forms the loop 8 is flattened and of an increased width, and its side faces are made concave, 65 as clearly shown in Fig. 3, so as to direct the hook 12 through the loop.

A pocket 13 is formed in the bottle by means of the frusto-conical wall 14 which extends inwardly from the bottom 7 and 70 which has a retaining flange 15 surrounding its inner end. The pocket 13 tapers toward the neck of the bottle and the annular flange 15 extends into said pocket in spaced relationship to the walls thereof.

When the stopper is removed from the bottle, the loop 8 is broken and the particles of glass drop into the pocket 13 wherein they are retained by means of the flange 15.

It will be seen from the foregoing description in connection with the accompanying drawings, that I have provided a simple non-resealable bottle which may be initially sealed without trouble but which cannot be resealed after the seal has once been broken. 85 The pocket 13 prevents the particles of glass formed by breaking the loop 8, being carried through the neck of the bottle with the liquid.

Having thus described my invention, what I claim is:—

1. A bottle having a fragile member formed therein, a stopper, and resilient means rigidly secured to the stopper, said means having a hook formed on one end 95 thereof which lockingly engages the fragile member when the stopper is positioned.

2. The combination with a bottle having an apertured stem formed therein, of a stopper, and an inwardly extending hooked rod 100 for engagement with said apertured stem, the removal of the stopper and rod causing the stem to break.

3. The combination with a bottle, of an inwardly projecting stem formed on the bottom thereof, said stem being flattened at its free end and apertured, a stopper, and a spring rod rigidly secured to said stopper, the rod being bent at its free end for engagement with the apertured stem, the positioning of the stopper causing said rod to project through said aperture, and the re-

moval of the stopper and rod causing the walls of the aperture to be broken.

4. The combination with a bottle having an apertured stem formed therein, of a stopper, an inwardly extending hooked rod carried by said stopper for engagement with said apertured stem, the removal of the stopper and rod causing the stem to be broken, and means for retaining the broken particles 10 of the stem within the bottle.

5. The combination with a bottle having an apertured stem formed therein, of a stopper, an inwardly extending hooked rod carried by said stopper for engagement with 15 said apertured stem, the removal of the stopper and rod causing the stem to be broken, a frusto-conical wall formed upon the bottom of the bottle and surrounding said stem, and a retaining flange formed upon the inner free end of the wall, whereby the particles of broken glass are retained within 20 the bottle.

6. The combination with a bottle, of an inwardly projecting stem formed centrally 25 of the bottom thereof, said stem being flattened at its inner end and of an increased width, the flattened portion being longitudinally slotted and having its side faces formed concave, a stopper, and a spring rod

rigidly secured to said stopper, the rod being bent at its free extremity for engagement with the slotted stem, the positioning of the stopper causing said rod to project through the slot, and the removal of the stopper and rod causing the walls of the slot 30 35 to be broken.

7. The combination with a bottle, of a fragile member formed therein, means closing the bottle and connected to the fragile member, the withdrawal of said means causing 40 the fragile member to be broken, and means for retaining the fragments of the fragile member within the bottle.

8. The combination with a bottle, of an easily breakable fragile member formed 45 therein, a stopper, a connection between the stopper and fragile member whereby the latter is broken when the stopper is withdrawn, and means surrounding the fragile member 50 for retaining the fragments thereof within the bottle.

In testimony whereof I affix my signature in presence of two witnesses.

FRANK A. MCGUIRE.
